UNITED STATES PATENT OFFICE.

WILLIAM J. HOOPER, OF BERKELEY, CALIFORNIA.

SEPARATOR.

Application filed August 13, 1924. Serial No. 731,752.

To all whom it may concern:

Be it known that I, WILLIAM J. HOOPER, a citizen of the United States, and a resident of the city of Berkeley, in the county of Alameda and State of California, have invented a new and useful Separator, of which the following is a specification.

This invention relates to a device for separating particles suspended in a gas or carried by a gaseous stream. Such a device may be arranged in the path of movement of the gaseous stream, and the gas in moving through the device is caused to separate from the particles carried thereby, whether these particles be very fine, as found in steam or smoke, or of comparatively large size, as glowing cinders in a smoke stack or flue.

It has been proposed in the past to provide such separators in which helicoidal passageways are provided for the gaseous stream. The suspended particles carried into the passageways by the stream are urged by centrifugal force due to the rotary motion in the passageways, away from the axis of the stream and through appropriate openings leading to another receptacle where the particles are collected and removed.

It is one of the objects of my invention to improve in general separators of this character, and to make it possible for such separators to extract more perfectly the particles carried by the stream.

In this connection it is a further object of my invention to provide substantially continuous spiral-like passageways between an outer collecting chamber and the inner chamber through which the gaseous stream passes. Due to this construction the separated particles are guided substantially continuously to the external collecting chamber through expanding passages.

My invention possesses other advantageous features, some of which with the foregoing, will be set forth at length in the following description, where I shall outline in full that form of the invention which I have selected for illustration in the drawings accompanying and forming part of the present specification.

Although I have shown in the drawings but one form of my invention, I do not desire to be limited thereto, since the invention as defined in the claims, may be embodied in other forms also.

Referring to the drawings:

Figure 1 is a longitudinal sectional view of a device embodying my invention;

Fig. 2 is a sectional view taken along the plane 2—2 of Fig. 1;

Fig. 3 is a longitudinal section along plane 3—3 of Fig. 2; and

Fig. 4 is a section of the spiral strip which forms the helicoidal passageway in the inner chamber.

The separator has an intake nozzle or passageway 11 near the bottom thereof as shown in Fig. 1. At the top the outgoing passageway 4 is shown, whence the purified stream may be conducted to any desired locality or to the atmosphere. The separator has an inner chamber formed by a series of overlapping vanes 6 (Fig. 2), forming tangential slots connecting this inner chamber with an external annular chamber 12, formed by the aid of an external wall 7. These vanes serve as deflectors and are preferably substantially spiral in cross section. The chamber formed by wall 7 may connect in turn to a collecting space, which may be provided either by a separate vessel or integrally, as is shown in the present instance. Thus the wall 7 is shown as formed integrally with a base 13, having a sloping interior surface 14 leading to a discharging outlet 15. The outer chamber 7 is closed at the top by the cover 17, which also serves to hold the vanes 6 in a rigid manner, and to provide the discharge outlet 4. This cover 17 may be fastened in any appropriate manner to the outer wall 7, as by the aid of the overhanging walls of the cover.

In order that the suspended particles carried by the gaseous stream be urged through the slots formed between the vanes 6, it is necessary to cause the gaseous stream to rotate, at the same time that it advances through the inner chamber formed by the vanes 6. This is effected by the aid of a spiralling strip 5 shown in greater detail in Figs. 3 and 4. This strip 5 is twisted to form a pair of helicoidal passageways for the gases through this inner space. The pitch of the helicoid is quite steep, and its length is substantially identical with the length of the vanes 6, as shown most clearly in Fig. 3. As the gases pass through nozzle 11 they divide into two streams which are separated by the strip 5. The gases are thus given a spiral rotary motion through the inner chamber. The particles carried by the

stream are caused due to the motion of the stream to move outwardly towards the slots between the overlapping vanes 6 and finally to enter into the outer chamber 12. They 5 then settle near to the outlet aperture 13, where they may be from time to time, or continuously, removed by the force of gravity or by other means, such as a suction pump, etc.

19 One important feature of my invention resides in the form of the strip 5. This strip has its edges extended so as to reach entirely across from one vane 6 to the diametrically opposite vane 6, as clearly shown in Fig. 2. 15 In this way the external diameter of the resultant helicoid is not uniform, but varies periodically in accordance with the varying diameter of the inner chamber defined by the inner surfaces of vanes 6. Furthermore, it 20 has extensions 8 (Fig. 4) which extend between the overlapping portions of vanes 6, and clear to the outer chamber 12. This is indicated most clearly in Figs. 1 and 3. 25 Slots 16 are of course provided between extensions 8 and the inner portion of strip 5, to accommodate the edges of the inner of the two overlapping vanes 6. These extensions 30 8 with the vanes 6 thus form a plurality of separate and distinct continuous spiral passageways between the inner and outer chambers. This construction in actual trial has proven to be highly efficient and a great deal more effective than prior schemes in which no such spiral passageways are found, since 35 the particles separated from the stream are continuously and effectively guided out of the inner chamber.

In order to assist in guiding the particles smoothly from the inner to the outer chamber, I show the cross section of the strip 5

nonradial; although other forms may be adopted; in this instance it is doubly curved, as clearly indicated in Figs. 2 and 4. Although this is not absolutely essential, it assists materially in the operation of the device. 45

The manner of use of the separator is evident from the foregoing. The nozzle 11 is arranged in the path of a gaseous stream to be purified. For example the nozzle 11 may 50 be attached to the discharge end of an ordinary vacuum sweeper, or it may be attached to a flue for the purpose of arresting sparks, collecting soot, or reducing smoke. 55

I claim:

1. In a separator, a series of substantially spiral overlapping vanes forming a series of openings, and a substantially helicoidal strip surrounded by the vanes, said strip extending at its edges entirely to the inner surfaces of the vanes. 60

2. In a separator, a series of spiral overlapping vanes forming an interior chamber with a series of longitudinal slots, and a substantially helicoidal strip in said chamber, the edges of the strip having extensions entering between the overlapping portions of the vanes and forming a series of substantially continuous passageways from the interior to the exterior of the chamber. 65

3. In a separator, a series of spiral overlapping vanes defining a chamber, means in this chamber for imparting a rotary motion to a gaseous stream, and means forming a series of spiral passageways between the overlapping portions of the vanes. 70

In testimony whereof, I have hereunto set my hand.

WILLIAM J. HOOPER.
